(57) **CLAIM**

The ornamental design for a dog harness, as shown and described.

DESCRIPTION

FIG. 1 is a front perspective view of a dog harness, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view thereof, shown in a opened position of use for clarify of illustration.

The dash-dash broken lines showing stitching forms part of the claimed design. The broken lines showing the circular pattern illustrate portions of the dog harness that form no part of the claimed design.
